UNITED STATES PATENT OFFICE.

ABRAHAM B. CIBEL, OF BROOKLINE, MASSACHUSETTS, ASSIGNOR TO BOSTON DYE HOUSE, INC., OF MALDEN, MASSACHUSETTS, A CORPORATION OF MASSACHUSETTS.

DRYING APPARATUS.

Application filed November 27, 1925. Serial No. 71,696.

This invention pertains to apparatus useful in drying garments, rugs, textile fabrics of all sorts and is intended for use in laundries, dry cleaning establishments, etc., 5 it being equally adaptable to the drying of clothes that have been washed or to drying and deodorizing of fabrics that have been cleaned by gasoline, benzine or the like.

Devices of this character usually comprise 10 a housing within which is arranged a foraminous or perforated drum or basket within which the fabrics are placed and which is rotated or oscillated to tumble the garments about and thus to expose all portions there- 15 of to heated air. This tumbling of the garments produces a large amount of lint which sifts out of the drums or baskets and tends to settle and collect wherever a neighboring projection or a crevice produces an eddy or 20 quiet zone in the surrounding air. Usually heating devices, for example steam coils, are arranged within the housing in close proximity to the drum and such heating coils afford many inaccessible places for the 25 lodgment of lint with resulting danger of fire and interference with heat radiation from the coils and with the circulation of the air thereabout. Sparks or static elec- 30 tricity are frequently produced by friction in moving material or contact of metallic buttons etc., within the drum and if any large quantity of accumulated lint is present in the apparatus a disastrous fire or explosion may and frequently does occur, such a 35 danger being greater in cases when the lint is permeated with gasoline vapor or the like.

The casing employed for housing the drum or basket is usually provided with thin walls of sheet metal which offer little re- 40 sistance to the passage of heat from the interior of the structure so that a large percent of the heat supplied to the apparatus is radiated into the work room. The tempera- 45 ture in the work room is thus unduly increased, while from the heat standpoint the apparatus is extremely inefficient.

The principal objects of the present in- 50 vention are to provide apparatus of the class described in which the lint is delivered from the drum into a large and un- obstructed settling chamber from which it may be removed frequently and without difficulty and, if desired, while the apparatus is in operation; to provide apparatus of this 55 type in which the heat is furnished from

an independent source outside of the housing so that the interior of the housing may be free from obstructions and so that one frequent cause of fire is eliminated; and to provide apparatus in which the heat supplied is employed economically and does not unduly raise the temperature of the work room.

Further objects of my invention will appear to those skilled in the art from a reading of the subjoined description in connection with the accompanying drawings which are to be considered as only illustrative of a preferred embodiment of my invention and in no way as limiting the scope thereof.

In the drawings:

Fig. 1 is a front elevation of my improved drying apparatus;

Fig. 2 is a transverse cross-section thereof; Fig. 3 is a longitudinal cross-section of the same;

Fig. 4 is a transverse cross-sectional view of the drying tumbler drum; and

Fig. 5 is a detailed section.

In the embodiment of my invention shown in the drawings, the walls of the housing 1 comprise inner and outer sheathings 2 and 3 with a space therebetween filled with any suitable heat insulating material 4 such as asbestos or the like. The doors 6 and 7 which extend to substantially the full height of the casing 1 fit snugly so that when closed they make the casing practically airtight and when opened they render practically the entire interior thereof readily accessible. These doors may or may not be filled with packing material but at any case have inner and outer walls 9 and 10 with a space therebetween to afford heat insulation. Any means, such as the small doors 11 and 12 at the top of the casing, which are normally held closed by their own weight, may be provided to relieve the increased pressure in case of an accidental explosion.

An inlet pipe 14 for delivering hot air to the casing is joined to the top of the casing 1 by a flared extension 15, while at the bottom of the casing is a longitudinal outlet pipe 17, which is preferably considerably smaller in cross-sectional area than the inlet pipe. This pipe 17 extends in a substantially horizontal direction through the lower part of the casing 1 at a substantial distance from its bottom and has the upwardly disposed intake openings 18 and 19.

and the downwardly disposed opening 16, covered with meshed wire. These openings are located to produce an effective circulation of air at all parts of the device and to avoid formation of pockets of inert inflammable gases.

The pipes 14 and 17 are adapted to be connected with any suitable air heating and circulating mechanism which will force a draft of air through the housing which may be one of a series of like devices.

The drum 25 may be of any ordinary form but I prefer a container having circular heads 26 connected by longitudinal members 27 which may be of any conventional cross-section but which are here shown as being U-shaped. The meshed wire 30 is secured upon this cylindrical framework and reinforcing hoops 28 are placed at suitable intervals along its length, portions of two of these hoops defining ends of an opening for a hinged door 31 which provides access to the interior of the drying drum. The ends of the drum 25 are mounted upon bearings 34 upon which it may be rotated or oscillated in any desired manner by driving mechanism 37 of any conventional type. It is to be noted that the drum 25 is substantially spaced from the bottom of the casing 1 to provide a large settling chamber and that there is a considerable clearance between the drum and the pipe 17.

The inner surface of the wall of the housing is smooth and free from projections, the floor is smooth and preferably horizontal, and the space within the housing is free of heating coils or other elements providing inaccessible surfaces or spaces for the lodging of lint.

In the operation of my device, fabrics or garments to be dried or deodorized are placed in the drum 25 and the doors 6, 7 and 31 being closed, hot air is then forced or drawn through the inlet pipe 14, passing down, around and through the drum 25, and out through openings 16, 18 and 19 of the outlet pipe. Any lint which has been formed by the movement of the garments in the drum 25 settles downwardly into the atmosphere below the drum and is deposited upon the floor of the housing or upon the pipe 17. The large doors 6 and 7 and the relatively large space about pipe 17 facil-

tate the manual removal of the lint from these parts from time to time.

The downwardly directed current of air assists gravity in causing the lint to settle into an accessible portion of the drying device where it can readily be removed as conditions demand while the larger wall area necessitated by the provision of the large settling chamber does not materially lower the thermal efficiency of the device due to the insulation 4 provided within the walls of the housing.

I claim:

1. Apparatus of the class described comprising an outer casing and an inner movable drum, an air inlet opening in the casing and a tubular member extending into the casing, and air inlet openings disposed at various points in the walls of the tubular member to induce a thorough circulation of air through the casing.

2. Apparatus of the class described comprising a casing having walls consisting of spaced inner and outer sheathings with heat insulating material interposed between them, said casing having an inlet for heated air at its top, an apertured tumbler drum for the reception of the garments to be treated, the space above the drum being free and unobstructed to facilitate distribution of the entering air, said drum being so disposed that its peripheral surface is spaced substantially from the floor of the casing to provide a lint settling chamber of large capacity, and an educt pipe extending into said chamber and spaced from the floor thereof, said pipe having a screened intake opening.

3. Apparatus of the class described comprising a casing having heat insulating walls, the inner surfaces of the walls of the casing being substantially smooth and free from lint collecting projections, a tumbler drum within the casing, the drum being spaced from the floor of the casing to provide a lint settling chamber of large capacity, and an educt pipe extending horizontally of the settling chamber and spaced from the floor of the latter, said pipe having at least one screened intake opening.

Signed by me at Malden, Mass., this 21st day of November, 1925.

ABRAHAM B. CIBEL.
